PORTABLE CHECKING COUNTER

James A. Davenport, Cincinnati, Ohio, assignor
to The Kroger Grocery & Baking Company,
Cincinnati, Ohio

Application February 2, 1946, Serial No. 645,149

4 Claims. (Cl. 280—36)

1

This invention relates to merchandising, and more particularly to selling in self-service stores, including the equipment employed in such stores. The invention particularly relates to a combined vehicle and counter for self-service stores, constructed to be used both for the collection and transportation of articles purchased, and also providing a surface on which the articles may be checked by a cashier.

Vehicles of various types, some with shelves or removable baskets, have been employed in self-service stores for use by the customer in collecting and carrying merchandise. These vehicles are usually pushed by the customer to a cashier's station or checking counter, where they are unloaded either by removing the articles directly from the baskets or containers of the vehicle, or by removing the basket from the vehicle and placing it on the counter and thereafter removing the articles from such basket or container.

When used in this manner it has been necessary that the merchandise be handled at least three or four times, namely,

- (1) Placing the articles in the basket or container;
- (2) Placing the basket on the counter;
- (3) Removing the articles from the basket for checking, and
- (4) Sacking the articles

Self-service stores came into being on account of the desire to increase sales and decrease time and effort in selling and handling. These essentials are still important and improvement thereon is very desirable.

Accordingly, the present invention provides a portable, collection and checking vehicle, the collection portion of the vehicle serving as a checking counter on which the articles are placed by the customer when they are collected, the vehicle being wheeled to the location of the checker or cashier, whereupon they are placed in bags to be taken out by the customers. The merchandise is therefore handled only twice instead of four times.

It is an object of the invention to facilitate the handling of merchandise in a self-service store by providing equipment for handling articles simply, efficiently, and in the least time possible, with minimum effort and expense on the part of all concerned, as well as to utilize maximum floor space to the best advantage and accelerate movement of traffic.

Another object of the invention is to reduce the amount of handling of the merchandise, as

2

well as to eliminate the usual checking counter, and consequently save a corresponding amount of floor space.

A further object of the invention is to provide a portable vehicle capable of being used for the collection and transportation of articles, and as a counter or platform on which the articles may be checked, such counter or platform having a surface of a character to facilitate the segregation and checking of the articles while not interfering with the collection of the articles.

A still further object resides in the provision of an improved package carrier for use in a self-service grocery store, such carrier being mounted on suitable wheels for movement by the customer and having a single level package receiving compartment of sufficient area to receive an entire normal order of groceries, said compartment being adjustable in size to render it capable of carrying an entire order without taking up an unnecessary amount of space.

Yet another object resides in the provision of an improved wheel supported package carrier having a single level package receiving compartment, so constructed and arranged that it has a high degree of stability and will not normally tip over even though the single level compartment is heavily loaded.

Further objects and advantages of the invention will be apparent from the following description taken in conjunction with the accompanying drawings, wherein:

Figure 1 is a perspective view of an improved mobile, package carrier constructed according to the invention;

Fig. 2, a top plan view of the package receiving compartment of the carrier illustrated in Fig. 1, certain parts being broken away and shown in section to better illustrate the construction thereof;

Fig. 3, a longitudinal sectional view on the line 3—3 of Fig. 2;

Fig. 4, a transverse sectional view on the line 4—4 of Fig. 2; and

Fig. 5, an end view on a somewhat reduced scale of the right hand end of the compartments illustrated in Fig. 2.

With continued reference to the drawings and particularly to Fig. 1, the improved package carrier comprises a carriage generally indicated at 10 and a package receiving compartment generally indicated at 12.

The carriage is supported upon two pairs of wheels or rollers. The larger wheels 14 and 16 are mounted upon the end portions of a continu-

ous axle 18 which projects beyond the wheels to respective operative connections with the frame members 20 and 22. The smaller wheels 24 and 26 are mounted in respective casters 28 and 30 secured to extensions 32 and 34 provided on the leg portions 36 and 38 of a continuous U-shaped frame member, the leg portions of which are connected by the intermediate portion 40.

The frame member 20 and the leg 36 are pivoted together intermediate their length and constitute one side of a double X frame upon which the compartment 12 is supported. The frame member 22 and the leg 38 pivotally connected at 42 intermediate their length constitute the other side of the X frame.

The lower ends of the frame members are operatively connected together by means of a pivoted brace generally indicated at 44 and comprising a U-shaped member having legs 46 and 48 and an intermediate connecting portion 50. At the open end of this brace the leg portions are pivotally connected to the frame members 20 and 22 adjacent the connections of the axle 18 with these frame members and intermediate their length the legs of the brace are pivotally connected at 52 and 54 with respective arms 56 and 58 which project from the respective extensions 32 and 34 toward the wheels 14 and 16. The intermediate connecting portion 50 is preferably somewhat shorter than the distance between the frame members 20 and 22 so that despite the offset shown in the members 46 and 48, there is no appreciable contact between these members and the frame members 20 and 22 when the portion 50 is elevated.

With this construction if the intermediate portion 50 of the brace is manually raised the lower ends of the frame members 20 and 22 will be moved toward the intermediate portion 40 of the associated frame member and the frame will be folded together in a manner such that it will occupy the minimum space for storage or shipment.

The intermediate portion 40 of the frame member comprising the legs 36 and 38 is disposed on the side of the caster wheels 24 and 26 remote from the wheels 14 and 16 and at such a level with respect to the axes of the caster wheels that it will strike the floor if the wheels 14 and 16 are raised a short distance above the floor level. This arrangement effectively prevents tipping of the carriage in the forward direction even though the compartment 12 should be heavily loaded. The wheels 14 and 16 are so positioned with respect to the area of the compartment 12 that tipping of the carriage to the left, as viewed in Fig. 1, is definitely avoided.

At their upper ends the frame members 20 and 22 are pivotally connected to a transverse rod or bar 60 which secures the upper ends of these members together and reinforces the frame to materially increase the rigidity thereof. The upper ends of the legs 36 and 38 of the corresponding frame member are pivotally connected to the sides of a table or platform 62 adjacent the left hand end of the platform as viewed in Fig. 1. At its opposite or right hand end the platform 62 is provided with downwardly extending lugs or projections, one of which is indicated at 64.

With this arrangement the platform 62 positively spaces the upper ends of the frame members and provides substantial reinforcement therefor. However, when the frame is folded the right hand end of the platform may be swung upwardly about the pivotal connections between 75

the platform and the frame members 36 and 38 and turned to a position in which it lies alongside the folded frame.

The compartment 12 comprises two telescopically associated tray members 66 and 68. The larger member 66 overlies the upper surface of the table or platform 62 and projects somewhat beyond the right hand end thereof as viewed in Fig. 1. This member is permanently secured to the table element 62 of the carriage. The tray member 68 fits into the tray member 66 and projects beyond the left hand end thereof as viewed in Fig. 1. The tray member 68 is held in telescopic association with the tray member 66 by suitable means which may comprise grooves 72 and 74 provided in the inner walls of the side members 76 and 78 of the tray member 66 and suitable rollers or pins 80 and 82 secured in the side walls of the tray member 68 and extending respectively into the grooves 72 and 74. In order to render the tray member 68 readily movable with respect to the tray member 66, antifriction means may be provided between the two members. This means may conveniently comprise four rollers as indicated at 84, 86, 88 and 90. The rollers 84 and 86 are preferably secured to the bottom 92 of the tray member 66 while the rollers 88 and 90 are secured to the bottom 94 of the tray member 68. The two trays may be releasably latched together in retracted position by means of one or more spring-biased pins or detents, as indicated at 96 seated in the bottom 92 of the outer tray member and engageable in grooves or depressions provided in the under surface of the bottom 94 of the inner tray member. These latching members are so formed that they will be released upon a reasonable force being exerted in a manner to extend the tray member 68 relative to the tray member 66.

40 The tray member 66 is provided with an end closing wall 98 against which the ends of the side members of tray member 68 abut to determine the limiting relative position of the two tray members when fully retracted. The relative position of the two tray members when fully extended is determined by the extent of the grooves 72 and 74. The ends of the side members 76 and 78 of the outer tray member opposite the end closure 98 are rounded off as indicated at 100 to 45 provide a smooth surface which will permit relative sliding of the two tray members without danger of material being caught between the two members during the relative movement or the fingers of the customer being injured by these 50 parts of the device.

In addition to the bottom 94 and side members 102 and 104, the inner tray member 68 is provided with an end closure member 106 which may have hand holes 108 and 110 provided therein for easier manipulation of the slidible tray member.

55 Preferably the space within the inner tray member 68 is divided into separate zones or areas by suitable means such as the painted-on lines 112 and 114, these separate zones or areas being respectively labeled as for grocery items, meat items and fruits and vegetables, as is clearly shown in Fig. 1. Preferably a portion of the bottom 94 in the fruits and vegetable zone is cut away and the space filled in by a suitable grid 116 of woven wire, expanded metal or other suitable construction, to provided for drainage of any moisture that may drip from grocery items deposited therein. In the event that moisture or liquid may be deposited or collected in the por-

tions of the package carrying compartment having a solid or continuous bottom wall, openings are provided in the outer tray at the right hand corner thereof as viewed in Fig. 1 and as indicated at 118 and 120 in Figs. 1 and 5. These openings may conveniently be provided by diagonally cutting off the corners of the outer tray member after its various components have been assembled together in operative position.

As explained above, the package carrying compartment 12 comprising the tray members 66 and 68 is supported at substantially the height of a conventional grocery checking counter and the compartment is of sufficient size to carry a normal complete order of groceries on a single level. In the retracted or collapsed condition of the two members 66 and 68, the compartment takes up a minimum amount of space but the available area may be readily increased by sliding the tray member 68 outwardly relative to the member 66 until sufficient space has been provided for the particular order. With the various packages arranged on the single level and supported at the convenient height indicated, the packages may be checked without removing them from the package receiving compartment and after they have been checked and charged the carrier may be moved to a convenient station at which the packages are removed and placed in suitable bags or other containers for removal from the store.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A mobile package container comprising a double X frame forming a carriage, wheels disposed at each end of the frame elements, a top member pivotally secured to one side of said frame and releasably engaged with the other side thereof, a single level package receiving compartment supported by said top member, said compartment comprising a pair of open-ended tray elements disposed in telescopic relationship, and a support element for preventing longitudinal upsetting of the carriage when the compartment is overloaded, said support element comprising a frame element extending transversely between the X frame elements exterior of one of the pairs of wheels and only slightly above the ground level, whereby upon tipping of the carriage the frame element will contact the ground and prevent over-turning.

2. A mobile package container comprising; a foldable metal frame, a top member for said frame, and a package receiving compartment of variable capacity mounted on said top member, said compartment composed of a fixed open ended tray and a shiftable open ended tray arranged in telescopic relationship, one of said trays having a bottom member including a drainage grid adjacent the closed end thereof, and

5 including also a solid portion, the other tray having a drainage slot near its closed end, whereby moisture from vegetables and fruits placed in the compartment will drain freely from said compartment when said trays are in either extended or telescoped relationship.

3. A mobile package container comprising: an adjustable package receiving compartment, said compartment comprising a pair of open ended tray elements slidably arranged in telescopic relationship; a carriage which is collapsible in a vertical plane comprising; four elevating members arranged in paired pivotal relationship, wheels mounted on the lower ends of said elevating members, a top member to support said compartment, said top member pivotally mounted at one end to two of said elevating members and releasably engaged at the other end with the other two elevating members, whereby said top member and said compartment can be swung into substantial alignment with said frame when said frame is in a collapsed position.

4. A portable checking counter comprising a carriage, wheels mounted on the underside of said carriage, an adjustable package compartment of variable capacity mounted on said carriage, said compartment comprising two open-ended trays arranged in telescopic relationship, one of said trays having a solid bottom for receiving dry commodities, the other of said trays being longer than the first tray and having a drain element arranged at its endwise portion whereby said drain element will extend beyond said solid tray and moisture will drain freely from wet produce placed on said element, even when said trays are in fully telescoped relationship.

JAMES. A. DAVENPORT.
